CLOSURE PLUG SET

Ferdinando De Amicis, 6641 Upton Ave. S.,
Minneapolis, Minn. 55423

Filed May 17, 1974, Ser. No. 470,997

Term of patent 14 years

Int. Cl. D9—07

U.S. Cl. D9—281

FIG. 1

FIG. 2

FIG. 3

FIG. 1 is a perspective view of a closure plug set showing my new design;

FIG. 2 is a rear perspective view thereof; and

FIG. 3 is a cross-sectional view taken along line 3—3 of FIG. 1.

I claim:

The ornamental design for a closure plug set, as shown and described.
